(57) **CLAIM**

The ornamental design for a treatment apparatus for endoscope, as shown and described.

DESCRIPTION

FIG. 1 is a front elevation view of a treatment apparatus for endoscope. The parallel vertical chain lines shown in the drawing show the part omitted since this article is a long object.

FIG. 2 is a rear elevation view thereof. The parallel vertical chain lines shown in the drawing show the part omitted since this article is a long object.

FIG. 3 is a top plan view thereof. The parallel vertical chain lines shown in the drawing show the part omitted since this article is a long object.

FIG. 4 is a bottom plan view thereof. The parallel vertical chain lines shown in the drawing show the part omitted since this article is a long object.

FIG. 5 is a left side elevation view thereof.

FIG. 6 is a right side elevation view thereof.

FIG. 7 is an enlarged front view thereof.

FIG. 8 is an enlarged top plan view thereof.

FIG. 9 is an enlarged bottom plan view thereof; and,

FIG. 10 is an enlarged left side view thereof.

The portion of the article shown in broken lines is for illustrative purposes only and forms no part of the claimed design.
